CLAIM

The ornamental design for a respirator mask, as shown and described.

DESCRIPTION

FIG. 1 is a perspective view showing the new design for a respirator mask;

FIG. 2 is a front view thereof;

FIG. 3 is a rear view thereof;

FIG. 4 is a right side view thereof, the left side being a mirror image thereof;

FIG. 5 is a top view thereof; and,

FIG. 6 is a bottom view thereof.

The dash-dash broken lines in the drawings illustrate portions of the respirator mask that form no part of the claimed design.

The dot-dash broken lines in the figures immediately adjacent the solid lines represent a boundary between claimed and unclaimed subject matter and form no part of the claimed design.
